UNITED STATES PATENT OFFICE.

EDWARD WILSON, OF ST. LOUIS, MISSOURI, ASSIGNOR TO WILSON ENGINEERING COMPANY, OF ST. LOUIS, MISSOURI, A CORPORATION OF MISSOURI

COMPRESSOR.

Application filed September 14, 1921. Serial No. 500,534.

To all whom it may concern:

Be it known that I, EDWARD WILSON, a citizen of the United States, residing at St. Louis, Missouri, have invented a new and useful Compressor, of which the following is a specification.

This invention relates to compressors.

An object of the invention is to provide a compressor which is highly efficient in its operation and which includes novel and improved valve mechanism for controlling the passages leading from the compression chambers through the cylinder structure.

Another object of the invention is to provide a compressor having oscillating pistons operating within a compression cylinder, a novel system of passages leading through the cylinder structure, and valves controlling the same.

Another object of the invention is to provide a compressor which is compact in assembly and in which parts of the operating mechanism are enclosed within a stationary support and immersed in oil, and in which the various operating parts are so arranged as to prevent excessive strains upon any of them.

Other objects of the invention and numerous advantages obtained thereby will be made apparent from the following description, reference being made to the accompanying drawings, in which—

Fig. 1 is a view partly in section and of a somewhat diagrammatic nature, showing parts of the invention.

Fig. 2 is a cross sectional view on the line 2—2 of Fig. 1.

Fig. 3 is an end elevation of the piston device and the cylinder in which it operates.

Fig. 4 is a sectional view on the line 4—4 of Fig. 3.

Fig. 5 is an elevation showing the inner side of one of the cylinder end walls, the inner sides of both end walls being alike.

Fig. 6 is a sectional view on the line 6—6 of Fig. 5.

Fig. 7 is a sectional view on the line 7—7 of Fig. 5.

Fig. 8 is a view showing a part of the valve construction.

The compressor, constituting the embodiment of my invention, is a compact arrangement in which the principal parts of the operative mechanism are enclosed within a case.

The operative mechanism of the compressor

is driven from a motor. In the embodiment of the invention shown, the motor rotates a drive shaft having connections for imparting oscillating or rocking movements to the piston shaft of the compressor by the continuous rotation of the rotary shaft in one direction. The connections from the rotary shaft to the piston shaft are preferably encased in a separate compartment from the compartment in which the compressor mechanism is enclosed.

As shown the base 1 constitutes the support for the compressor and for the motor 2. The motor 2 is arranged to operate the rotary shaft of the compressor by which the oscillating or rocking movements are imparted to the piston shaft.

The case or housing 3 of the compressor is mounted upon the base 1 and is provided with a removable end wall 4, constituting a support for the rotary shaft of the compressor. The rotary shaft 5 is journaled for rotation in anti-friction bearings 6 supported by the end wall 5, and is connected with the motor shaft by an appropriate coupling 7.

The inner side of the end wall 4 is dished or recessed to receive the ring 8 of the fly wheel. A disk or flange 9 is in rigid connection with the inner end of the shaft 5 and is attached to the ring 8 of the fly wheel. The fly wheel not only functions as such but also serves as a part of the connections for imparting oscillating or rocking movements to the compressor shaft by continuous rotation of the shaft 5 in one direction.

The disc 9 supports a wrist pin 10 eccentrically with respect to the axis of the shaft 5. The wrist pin 10 constitutes a support for an anti-friction bearing 11 upon which an arm 12 is mounted for rotation.

The oscillating or rocking piston shaft 13 has one end extending into the compartment in which the connections from the shaft 5 to said shaft 13 are contained. The end of the shaft 13 in said compartment is equipped with an arm 14 overlapping the end of the arm 12 and connected therewith by an anti-friction pivot device 15. By this construction oscillating or rocking movements are imparted to the shaft 13 by the continuous rotation of the shaft 5 in one direction. The support 10 for the arm 12 rotates around the plane of the axis of the shaft 13.

The housing 3 is provided with a parti-

tion wall 16 dividing the interior of the housing into two compartments. One of the compartments contains the connections from the shaft 5 to the shaft 13, and the other compartment contains the compression device.

The partition wall 16 is formed with an opening near the bottom of the housing. In said opening a bearing support 17 is secured, said support having a hole through its center through which the shaft 13 extends. The bearing support 17 sustains the anti-friction bearing 18 for one end of the shaft 13. The bearing 18 is within the compartment containing the connections from the shaft 5 to the shaft 13.

The opposite end of the shaft 13 is supported by an anti-friction bearing 19 carried by a removable end wall 20 for the housing 3. The end wall 20 supports an air chamber 21 into which air is admitted through an inlet 22 and from which the air passes into the opening or passage 23 in the hollow shaft 13. The outer end of the shaft 13 extends through the end wall of a cylindrical member 24 which opens into the air receiving chamber 21. A nut 25 screws onto the end of the shaft 13 and clamps the end of the cylindrical member 24 against the inner ring of the anti-friction bearing 19, which is also abutted against one of the end walls of the compression cylinder.

In the construction shown a cylinder 26 is in rigid connection with the removable end wall 20. A non-rotative cylinder 27 is mounted in the cylinder 26, but is capable of axial movements within the supporting cylinder 26 in order to maintain perfect adjustment of the parts and to permit the parts to be adjusted in accommodation to each other.

The cylinder 27 is provided with one or more compression chambers formed by inwardly extending sectors (Fig. 3) whose inner ends contact with the rocking piston shaft 13. The inner end of each of the sectors 28 is formed with a longitudinal groove in which a packing element 29 is located. The packing elements 29 extend the full length of the sectors 28 and have longitudinal channels in their outer sides containing springs 30 which press the packing elements in close contact with the periphery of the shaft 13 to form perfect seals to prevent air from passing thereby. The springs 30, as shown, are appropriately curved leaf springs having their ends bearing against the packing elements, and their arched or curved centers bearing against the bottom walls of the grooves in the sectors 28. The shaft 13 is provided with grooves 31 extending the full length of the compression chambers. The grooves 31 are formed so that at the end of the turning movements of the shaft 13 the packing elements 29 overlap the grooves. In the position of the shaft 13 shown in Fig. 3,

each of the packing elements 29 overlaps one of the grooves 31, and when the shaft 13 reaches the end of its turning movement in the opposite direction, the packing elements 29 overlap other grooves 31. Thus, each packing element 29 operates against only that peripheral portion of the shaft 13 which is between two of the grooves. This prevents the formation of ridges or irregularities on the periphery of the shaft by the packing elements.

The pistons are in the form of sectors 32 integral with the shaft 13 and arranged to operate within the compression chambers in the cylinder 27. The outer ends of the sectors 32 have the same curvature as the outer walls of the chambers within which the piston sectors operate, and are provided with longitudinal grooves containing packing elements 33 actuated by springs 34 similar to the springs 30 which actuate the packing elements 29. The packing elements 33 are pressed by the springs 34 into contact with the outer walls of the compression chambers to form perfect seals and prevent the air from passing thereby. The cylinder 27 has two longitudinal grooves 35 in each compression chamber located at the ends of the movement of the packing elements 33, so that said elements 33 will overlap the grooves 35 when the pistons 32 are at the end of their strokes. The presence of these grooves 35 prevents the packing elements 33 from wearing ridges or irregularities on the inner surface of the cylinder 27.

The end walls of the cylinder 27 comprise discs 36. The disc 36 at the outer end of the cylinder 27 has a hub contacting with the inner ring of the bearing 19. The outer disc 36 is keyed to, and rocks with, the shaft 13.

The disc 34 at the inner end of the cylinder 27 is attached to the pistons 32 by screws 37 passing through said disc and engaging in threaded holes in the pistons. A compression ring or gland 38 encircles the shaft 13 between the inner disc 36 and a flange 39 surrounding the hole in the support 17 through which the shaft 13 extends.

Oil inlets 40 are formed through one of the discs 36 (Fig. 6) to admit oil to the packing elements 34 to cooperate with said elements in forming perfect seals and to afford lubrication to cause said packing elements to function properly at all times. Oil inlets 41 (Fig. 4) are formed through the cylinder 27 and through the sectors 28 to admit oil to the packing elements 29. The oil so admitted to the packing elements 29 affords the desired lubrication and also operates with said elements to form perfect seals to prevent the passage of air thereby.

Air entering the passage 23 in the shaft 13 is admitted into the compression chambers. In the embodiment of the invention

shown, passages 42 (Fig. 4) constitute communication from the passage 23 in the shaft 13 to passages 43 in the discs 36. Since the discs 36 cannot turn relative to the shaft 13, the passages 43 are always in communication with the passage 23. From the passage 43 openings 44 are provided to admit the air into the compression chambers. The passages 43 and the openings 44 therefrom are alike in both discs 36. The passages 43 are arranged so that they alternate in admitting air into the different compression chambers. As shown in Fig. 3, the lower passage 43 is admitting air into one compression chamber while the opposite passage 43 is admitting air into the other compression chamber. When the pistons 32 move in a counter-clockwise direction, as shown in Fig. 3, the discs 36 move therewith and the passages 43 move around, so that the lower passages 43 are brought into communication with the other compression chamber while the upper passages 43 move around into communication with the compression chamber with which the lower passages were previously in communication.

Compression is effected by both pistons 32 on every stroke so that there is no lost motion or idle operation thereof. Each disc 36 is provided with two annular recesses 45 which function as passages through which the compressed air passes from the compression chambers through the valve controlled outlets, as will now be described.

Each sector 28 of the stationary cylinder 27 has a valve controlled passage therein with which the passages 45 are alternately brought into communication. As shown, each sector 28 is formed with a recess 46 (Fig. 4) opening at one end through a plate 47 embedded in the end of the sector. In the rocking of the pistons and the discs 36, the passages 45 are alternately moved into and out of communication with the openings 46 through the plates 47. This communication is effected as the pistons 32 approach the ends of their strokes, so that the compressed air passes from the compression chambers through the passages 45, through the openings in the plates 47, into the recesses 46, and out through openings 48 into a chamber 49 between the cylinders 26 and 27, which opens into the casing or housing 3 at the top (Fig. 1) above the level of the oil.

Within each recess 46 a valve 50 is located and pressed to closed position by a spring 51. The spring 51 in each recess is properly retained and guided by a retainer member 52 of smaller diameter than the diameter of the recess so as not to interfere with the passage of the air. The spring retainers 52 also serve to retain and guide the valves 50 properly. For this purpose the spring retainers 52 are formed at their valved ends with an annular series of tongues or pro-

jections 53 extending from radial arms 54 integral with the spring retainer. The valve 50 is within the annular series of tongues or projections 53 and guided thereby. The said tongues or projections are spaced apart so that when the valve 50 is pressed to open position by the pressure of the air within the compression chamber, the air will pass between said tongues or projections and fence around the spring retainer 52 through the opening 48. The radial arms 54 engage a shoulder in the recess 46 to support the spring retainer rigidly.

The two discs 36 are of duplicate construction but the passages 45 in one of said discs 36 cooperate with one of the valve controlled outlet passages in the manner described, while the passages 45 in the other disc 36 cooperate with the other valve controlled outlet passage. Thus, while the construction of the discs is the same, they occupy reverse or opposite positions relative to the pistons and the other parts of the machine.

Each of the discs 36 is formed with a pair of pressure relief passages 55, the inner ends of which open into the passage 43 and the outer ends of which are arranged to communicate alternately with passages 56 branching from the openings through one of the plates 47. The relief passages 55 are constructed and arranged so that at or about the time that the pistons 32 complete their strokes, one of the passages 55 in one disc 36 communicates with the branch 56, while one of the passages 55 in the other disc 36 communicates with the branch 56 of the other outlet passage, thus admitting the compressed air from the passages 45 and from the openings in the plates 46 into said passages 55. This will relieve the pressure against the influent side of the valves 50, due to the fact that, at the time this occurs, the passages 55 that are in communication with the branch passages 56 (Fig. 3), also communicate with the respective compression chambers as well as with the passage 23. Such communication is through the passages 43 into which the passages 55 open. Thus, at the end of each compression, the pressure against the influent sides of the valves 50 is relieved, permitting the valves to be closed quickly by the action of their springs 51, as well as by the pressure of the compressed air against the effluent sides of the valves.

In operation the running of the motor 2 imparts a continuous rotary motion to the shaft 5 which, by the connections therefrom, imparts rocking movements to the piston shaft 13 and to the pistons 32. The discs 36 are rocked with the shaft 13 and the pistons 32. The passages 43—44 are in constant communication with the inlet passage 23 and are alternately in communication with the respective compression chambers in

the cylinder 27. Air is thus admitted into the compression chambers alternately on opposite sides of the pistons 32. Each piston 32 effects compression on each turning 5 movement thereof. At the proper time the passages 45 are moved into communication with the valve controlled outlet passages respectively, thus causing the compressed air to be discharged through said outlet 10 passages into the case or housing 3 from which the compressed air may be conducted through a pipe 57. In order to effect instant closing of the valves 50, the relief passages 55-56 are provided and function in the manner 15 described.

From the foregoing it will be seen that my invention completely obtains all of its intended purposes and objects. The machine is highly efficient and is practically noiseless in operation and is practicable from 20 every standpoint.

I do not restrict myself to unessential features or limitations but what I claim and desire to secure by Letters Patent is:—

25 1. A compressor, comprising a cylinder, radial sectors extending inwardly from the cylinder, pistons within the cylinder between the radial sectors, and mechanism for imparting relative rocking movements 30 between the cylinder and the pistons; in combination with end walls for the cylinder secured to the rocking part, air inlet passages through the end walls for admitting air into the cylinder between said pistons 35 and said sectors, air outlet passages from the cylinder formed in part in the end walls and in part in said sectors, and valves in said outlet passages in the sectors permitting compressed air to pass from the cylinder through said passages.

40 2. A compressor, comprising a cylinder, radial sectors extending inwardly from the cylinder, pistons within the cylinder between the radial sectors, and mechanism 45 for imparting relative rocking movements between the cylinder and the pistons, in combination with end walls for the cylinder secured to the rocking part, air inlet passages through the end walls for admitting 50 air into the cylinder between said pistons and said sectors, air outlet passages from the cylinder formed in part in the end walls and in part in said sectors, valves in said outlet passages in the sectors permitting 55 compressed air to pass from the cylinder through said passages, means for relieving the pressure against the effluent sides of said valves, and springs for closing said valves.

60 3. A compressor, comprising a housing, a stationary cylinder within the housing, a rocking piston within the stationary cylinder, end walls for the cylinder arranged to rock with the piston, air inlet passages through the end walls for admitting air into 65 the cylinder, and a valve controlled outlet

passage permitting compressed air to pass from the cylinder.

4. A compressor, comprising a housing, a stationary cylinder within the housing, a non-rotative cylinder supported within the stationary cylinder, a shaft extending through the non-rotative cylinder, sectors in connection with the non-rotative cylinder extending to said shaft and dividing said cylinder into compression chambers, pistons in connection with said shaft in said chambers respectively, end walls for the non-rotative cylinder arranged to rock with the pistons, an air inlet passage in the shaft, passages in the end walls communicating with the air inlet passage in the shaft and arranged to communicate with the compression chambers respectively and successively, air outlet passages in said sectors, and passages in the end walls arranged to communicate respectively and successively with the passages in said sectors to permit compressed air to pass from the compression chambers.

5. A compressor, comprising a housing, a stationary cylinder within the housing, a non-rotative cylinder supported within the stationary cylinder, a shaft extending through the non-rotative cylinder, sectors in connection with the non-rotative cylinder extending to said shaft and dividing said cylinder into compression chambers, pistons in connection with said shaft in said chambers respectively, end walls for the non-rotative cylinder arranged to rock with the pistons, an air inlet passage in the shaft, passages in the end walls communicating with the air inlet passage in the shaft and arranged to communicate with the compression chambers respectively and successively, air outlet passages in said sectors, passages in the end walls arranged to communicate respectively and successively with the passages in said sectors to permit compressed air to pass from the compression chambers, a valve in each of the passages in said sectors arranged to be opened by the pressure of the compressed air within the compression chambers, and springs for closing said valves.

6. A compressor, comprising a housing, a stationary cylinder within the housing, a non-rotative cylinder supported within the stationary cylinder, a shaft extending through the non-rotative cylinder, sectors in connection with the non-rotative cylinder extending to said shaft and dividing said cylinder into compression chambers, pistons in connection with said shaft in said chambers respectively, end walls for the non-rotative cylinder arranged to rock with the pistons, an air inlet passage in the shaft, passages in the end walls communicating with the air inlet passage in the shaft and arranged to communicate with the compres-

sion chambers respectively and successively, air outlet passages in said sectors, passages in the end walls arranged to communicate respectively and successively with the passages in said sectors to permit compressed air to pass from the compression chambers, a valve in each of the passages in said sectors arranged to be opened by the pressure of the compressed air within the compression chambers, springs for closing said valves, and pressure relief ports for relieving the pressure against the influent sides of said valves to permit said springs to effect quick closing of the valves and to prevent return of the compressed air into the compression chambers.

7. A compressor, comprising a housing arranged to contain oil in the lower portion thereof, a stationary cylinder supported within the housing partly below the level of the oil, a non-rotative cylinder supported within the stationary cylinder and being capable of axial movement therein, a shaft extending axially through the non-rotative cylinder, sectors extending from the non-rotative cylinder to the shaft dividing the interior of said cylinder into compression chambers, pistons in said shaft in said compression chambers respectively, mechanism for rocking said shaft and thereby said pistons, end walls for the non-rotative cylinder arranged to rock with said shaft and with said pistons, passages in the end walls arranged to communicate with said compression chambers respectively and successively, air outlet passages from the compression chambers, and valves controlling said air outlet passages arranged to open by the pressure of the air within the compression chambers.

8. A compressor, comprising a housing arranged to contain oil in the lower portion thereof, a stationary cylinder supported within the housing partly below the level of the oil, a non-rotative cylinder supported within the stationary cylinder and being capable of axial movement therein, a shaft extending axially through the non-rotative cylinder, sectors extending from the non-rotative cylinder to the shaft dividing the interior of said cylinder into compression chambers, pistons on said shaft in said compression chambers respectively, mechanism for rocking said shaft and thereby said pistons, end walls for the non-rotative cylinder arranged to rock with said shaft and with said pistons, passages in the end walls arranged to communicate with said compression chambers respectively and successively, air outlet passages from the compression chambers, valves controlling said air outlet passages arranged to open by the pressure of the air within the compression chambers, springs for holding said valves in closed positions

and arranged to yield to permit said valves to be opened by the pressure of the air within the compression chambers, and means for relieving the pressure against the influent sides of said valves about the time that the compressed air has been forced from said chambers.

9. A compressor, comprising a housing, a non-rotative cylinder supported within the housing, compression chambers within the non-rotative cylinder, a shaft extending axially through said cylinder, pistons on said shaft in said compression chambers respectively, mechanism for rocking said shaft and thereby said pistons, end walls for the cylinder arranged to rock with said shaft and with said pistons, air inlet passages in said end walls for admitting the air into said compression chambers, and air outlet passages opened and closed by said end walls as an incident to the rocking movements of said end walls to permit said pistons to effect compression in said chambers and to permit the compressed air to pass from said compression chambers at the proper time.

10. A compressor, comprising a cylinder, compression chambers within the cylinder, a shaft extending axially through the cylinder, pistons on the shaft within the compression chambers, mechanism for rocking the shaft and the pistons to effect compression within the compression chambers, passages for conducting the compressed air from the compression chambers, and end walls for the cylinder controlling the passage of compressed air from said chambers.

11. A compressor, comprising a cylinder, compression chambers within the cylinder, a shaft extending axially through the cylinder, pistons on the shaft within said compression chambers, mechanism for rocking the shaft and the pistons to effect compression within the compression chambers, passages for conducting the compressed air from the compression chambers, end walls for the compression chambers controlling the passage of the compressed air from the compression chambers into said passages, valves in said passages arranged to be opened by the pressure of the compressed air within the compression chambers to permit the compressed air to pass from the compression chambers through said passages, and means for relieving the pressure against the influent side of said valves after the compressed air has passed from the compression chambers.

12. A compressor, comprising a cylinder, compression chambers within the cylinder, a shaft extending axially through the cylinder, pistons on the shaft within said compression chambers, mechanism for rocking the shaft and the pistons to effect compression within the compression chambers, passages for conducting the compressed air from the compression chambers, end walls

for the compression chambers controlling the passage of the compressed air from the compression chambers into said passages, valves in said passages arranged to be opened by 5 the pressure of the compressed air within the compression chambers to permit the compressed air to pass from the compression chambers through said passages, means for relieving the pressure against the influent side 10 of said valves after the compressed air has passed from the compression chambers, and means for effecting quick closing of the valves when the pressure against the influent side thereof is relieved to prevent the compressed air from turning into the compression chambers.

13. A compressor, comprising a cylinder, radial sectors extending inwardly from the cylinder, compression chambers in the cylinder between the radial sectors, a shaft extending axially through the cylinder and forming the inner walls of the compression chambers, pistons on the shaft in the compression chambers respectively, mechanism 20 for rocking said shaft and said pistons to effect compression in the compression chambers, and end walls for the compression chambers controlling the admission of air into the compression chambers and the discharge of compressed air from the compression chambers.

14. A compressor, comprising a cylinder, radial sectors extending inwardly from the cylinder, compression chambers in the cylinder between the radial sectors, a shaft extending axially through the cylinder, pistons on the shaft within the compression chambers, mechanism for rocking the shaft and the pistons to effect compression within 35 the compression chambers, end walls for the compression chambers controlling the admission of air into the compression chambers, passages for conducting the compressed air from the compression chambers, 40 means whereby the end walls control the admission of the compressed air into said passages, and means for preventing the compressed air from returning into the compression chambers through said passages.

15. A compressor, comprising a cylinder, compression chambers within the cylinder, a shaft extending axially through the cylinder, pistons on the shaft within the compression chambers, mechanism for rocking the 45 shaft and the pistons to effect compression within the compression chambers, and end walls for the compression chambers controlling the admission of air into said compression chambers and controlling the discharge 50 of the compressed air from the compression chambers.

16. A compressor, comprising a cylinder, compression chambers within the cylinder, a shaft extending axially through the cylinder, pistons on the shaft within the compres-

sion chambers, mechanism for rocking the shaft and the pistons to effect compression within the compression chambers, end walls for the compression chambers controlling the admission of air into said compression chambers and controlling the discharge of the compressed air from the compression chambers, means for operating the end walls to admit air into the compression chambers and to permit compressed air to pass from the compression chambers, and valves preventing the return of compressed air into the compression chambers.

17. A compressor, comprising a cylinder, a shaft extending axially through the cylinder, radial sectors in connection with the cylinder extending to the shaft, compression chambers in the cylinder between said sectors, pistons on the shaft within the compression chambers, passages for admitting air into the compression chambers, passages for conducting the compressed air from the compression chambers, end walls for the compression chambers controlling said passages, and means for operating said end walls to admit air into the cylinders through the admission passages and to permit compressed air to pass from the compression chambers through the other passages mentioned.

18. A compressor, comprising a cylinder, a shaft extending axially through the cylinder, radial sectors in connection with the cylinder extending to the shaft, compression chambers in the cylinder between said sectors, pistons on the shaft within the compression chambers, passages for admitting air into the compression chambers, passages for conducting the compressed air from the compression chambers, end walls for the compression chambers controlling said passages, means for operating said end walls to admit air into the cylinders through the admission passages and to permit compressed air to pass from the compression chambers through the other passages mentioned, valve mechanism preventing the compressed air from returning into the compression chambers, and means for controlling said valve mechanism.

19. A compressor, comprising a stationary cylinder, a non-rotative cylinder supported within the stationary cylinder for axial adjusting movements, a shaft extending axially through the non-rotative cylinder, sectors extending inwardly from the non-rotative cylinder to the shaft, compression chambers between said sectors, pistons on said shaft in said compression chambers, mechanism for rocking the shaft and the pistons to effect compression in the compression chambers, an end wall for the compression chambers keyed to the shaft for rocking movements therewith and for axial adjusting movements thereon, another end wall

- for the compression chambers attached to the pistons, passages controlled by said end walls and by said sectors for admitting air into the compression chambers, and valved 5 outlet passages for conducting the compressed air from the compression chambers.
20. A compressor, comprising a stationary cylinder, a non-rotative cylinder supported within the stationary cylinder for axial adjusting movements, a shaft extending axially through the non-rotative cylinder, sectors extending inwardly from the non-rotative cylinder to the shaft, compression chambers between said sectors, pistons 10 on said shaft in said compression chambers, mechanism for rocking the shaft and the pistons to effect compression within the compression chambers, an end wall for the compression chambers keyed to the shaft for 15 rocking movements therewith and for axial adjusting movements thereon, another end wall for the compression chambers attached to the pistons, passages controlled by said end walls and by said sectors for admitting 20 air into the compression chambers, a receiving chamber between the non-rotative cylinder and the stationary cylinder, passages for conducting compressed air from the compression chambers into the receiving chamber, and passages in the end walls for conducting the compressed air from the receiving chamber into said last-named passages.
21. A compressor, comprising a stationary cylinder, an axially movable non-rotative cylinder within the stationary cylinder, a compressed air receiving chamber between said two cylinders, compression chambers within the non-rotative cylinder, mechanism for effecting compression within the compression chambers, end walls for the compression chambers, and passages controlled 35 by said end walls for conducting the compressed air from the compression chambers into the receiving chamber.
22. A compressor, comprising a housing, a stationary cylinder within the housing, a non-rotative axially adjustable cylinder supported within the stationary cylinder, a receiving chamber between said two cylinders, compression chambers within the non-rotative cylinder, end walls for the compression chambers, mechanism for effecting compression within the compression chambers, air inlet passages for admitting air into the compression chambers, means cooperating 50 with the end walls for controlling admission of air into the compression chambers, and means cooperating with the end walls controlling the discharge of compressed air from the compression chambers into the receiving chambers.
23. A compressor, comprising a cylinder,
- end walls for the cylinder, mechanism for effecting compression for the cylinder, inlet passages for admitting air into the cylinder, 65 outlet passages for conducting the compressed air from the cylinder, and means for operating said end walls to open and to close said passages to control the admission of air into the cylinder and the discharge of compressed air therefrom.
24. A compressor, comprising a cylinder, end walls for the cylinder, mechanism for effecting compression for the cylinder, inlet passages for admitting air into the cylinder, 70 outlet passages for conducting the compressed air from the cylinder, means for operating said end walls to open and to close said passages to control the admission of air into the cylinder and the discharge of compressed air therefrom, valves in the passages for conducting compressed air from the cylinders, and means for operating said valves to closed position after the compressed air has been discharged from the cylinders to prevent the compressed air 75 from returning to the cylinders.
25. In a compressor, the combination of a cylinder, compression chambers in the cylinder, a rock shaft having an air inlet passage therethrough, pistons on said shaft operating within said compression chambers to effect compression therein, and end walls for said compression chambers operated by said shaft and having passages therein in 80 communication with said air inlet passage in said rock shaft to control the admission of air in one of said chambers and the discharge of compressed air from said chamber.
26. In a compressor, the combination of a cylinder, compression chambers in the cylinder, a rock shaft extending axially through the cylinder, pistons on said shaft in the compression chambers, and end walls for said compression chambers operated by said shaft and having passages controlling the admission of air into one of said chambers and the discharge of compressed air therefrom.
27. In a compressor, the combination of a cylinder, compression chambers in the cylinder, a shaft extending axially through said cylinder, pistons on said shaft in said compression chambers, mechanism for operating said shaft and said pistons to effect compression in said chambers, valved outlet passages for conducting the compressed air from said chambers, and means operated by said shaft controlling the admission of air into said chambers and the discharge of compressed air from said chambers through 105 said valved outlets.

EDWARD WILSON.
